CLAIM

The ornamental design for a electric mop as shown and described.

DESCRIPTION

FIG. 1 is a perspective view of a electric mop showing my new design;
 FIG. 2 is another perspective view thereof;
 FIG. 3 is a front view thereof;
 FIG. 4 is a back view thereof;
 FIG. 5 is a left view thereof;
 FIG. 6 is a right view thereof;
 FIG. 7 is a top plan view thereof;
 FIG. 8 is bottom plan view thereof;
 FIG. 9 is a partial enlarged view of portion 9 in FIG. 1;
 FIG. 10 is a partial enlarged view of portion 10 in FIG. 1;
 FIG. 11 is a partial enlarged view of portion 11 in FIG. 1;
 and,
 FIG. 12 is a partial enlarged view of portion 12 in FIG. 2.
 The broken lines depict portions of the electric mop and form no part of the claimed design.
